UNITED STATES PATENT OFFICE

132,040

DESIGN FOR A DOOR OR SIMILAR ARTICLE

Margery Cummings, Beverly Hills, Calif.

Application October 27, 1941, Serial No. 103,905

Term of patent 3½ years

To all whom it may concern:

Be it known that I, Margery Cummings, a citizen of the United States, residing in the city of Beverly Hills, in the county of Los Angeles, State of California, have invented a new, original, and ornamental Design for a Door or Similar Article, of which the following is a specification, reference being had to the accompanying drawing, forming a part thereof.

The drawing is shaded to show contrasting color.

The characteristic features of my design reside in a door embodying a central panel and imitation saddle stitching forming a border around the said central panel, as shown.

I claim:

The ornamental design for a door or similar article, substantially as shown and described.

MARGERY CUMMINGS.
